UNITED STATES PATENT OFFICE.

OSCAR SIDEL, OF COLDEN, NEW YORK.

YIELDING FURNITURE-SUPPORT.

1,273,939.

Specification of Letters Patent. Patented July 30, 1918.

Application filed April 27, 1917. Serial No. 164,948.

To all whom it may concern:

Be it known that I, OSCAR SIDEL, a citizen of the United States, residing at Colden, in the county of Erie and State of New York, 5 have invented new and useful Improvements in Yielding Furniture-Supports, of which the following is a specification.

This invention relates to a yielding support for furniture so as to enable the same 10 to rest evenly upon a floor in case there is some irregularity in the construction of the furniture or the floor.

It is the object of this invention to provide a yielding support of this character 15 which is very simple and inexpensive in construction, which can be readily applied to the legs or other members of tables or similar pieces of furniture and which operates to effectively maintain the table 20 evenly on the floor, so that the same will not vibrate or tilt objectionably when in use.

In the accompanying drawings:

Figure 1 is a vertical section of a table leg provided with my improved yielding support. Fig. 2 is a horizontal section of the same taken on line 2—2, Fig. 1.

Similar characters of reference indicate corresponding parts in both figures.

When applying my invention to a table leg 1 or similar member the latter is provided with a vertical cylindrical socket 2 which opens downwardly and has its lower end terminating in an annular rabbet 3 forming a downwardly facing shoulder.

My improved yielding support is mounted in this socket and preferably constructed as follows:

Within the socket is arranged a tubular guide which is divided diametrically and 40 lengthwise in two like sections each of which comprises a semi-cylindrical body 4 which engages with one side of the socket, an external segmental flange 5 arranged at the lower end of the body and engaging with one part of the rabbet at the lower end of 45 said socket, an internal segmental flange 6 arranged at the lower end of the body and forming an upwardly facing shoulder, and an upper internal segmental flange 7 arranged at the upper end of the body and forming a downwardly facing shoulder. The two sections of the guideway are 50 preferably held against each other and within the socket by friction and when in their proper position the opposing inner edges of the lower and upper internal flanges of these

sections together form lower and upper guide openings 8, 9 in the guide. Each of these guide sections has its body, lower external and internal flanges and its upper 60 internal flange preferably formed integrally of cast metal.

10 represents an upright supporting rod which moves vertically in the guide and engages its lower and upper parts in the corresponding openings thereof. At its lower end the supporting rod is provided with a shoe 11 preferably of semi-globular form, which is adapted to rest on the floor, and within the guide this supporting rod is provided with a stop collar 12 which is adapted to bear with its underside against the upwardly facing shoulder of the guide. This supporting rod together with its shoe and stop collar are preferably formed integrally 70 of metal.

13 represents a helical spring surrounding the upper part of the supporting rod within the tubular guide and bearing at its lower end against the upper side of the collar 12 while its upper end bears against the downwardly facing shoulders of the guide sections. This spring is sufficiently stiff to form a reliable support for the weight of the table which is imposed upon this leg 80 and still permit the same to yield sufficiently to cause an evenness effect upon the table in the event that the floor or the table is of somewhat uneven or irregular construction. By this means disagreeable tilting or vibration of the table is avoided which otherwise would result when a floor is uneven or the legs of the table are of uneven length.

This yielding support can be produced at comparatively low cost on account of the 90 few parts which enter into its manufacture and by reason of its simplicity of construction the same can also be easily applied to a furniture leg or member by simply boring a socket in the latter. This yielding support therefore requires no special tools for applying the same to a furniture leg nor does it require any unusual alteration in the furniture for applying the same thereto, thereby enabling a person having but little 100 skill in the use of tools to properly mount this yielding support on table legs or similar kinds of furniture.

I claim as my invention:

A furniture support comprising a guide 110 adapted to be inserted in a socket in a furniture member and consisting of two like

sections each of which comprises a semi-cylindrical body, a lower upwardly facing shoulder arranged on the interior of the lower part of said body and an upper downwardly facing shoulder arranged on the interior of the upper part of said body, each section having its body and upper and lower shoulders formed integrally, a supporting rod arranged between said sections and pro-

vided between the upper and lower shoulders thereof with an integral stop collar which engages with said lower shoulder, a spring surrounding said rod and engaging its lower end with said collar and its upper end with said upper shoulder, and a dome shaped shoe arranged on the lower end of said rod.

OSCAR SIDEL.
